UNITED STATES PATENT OFFICE.

CARL METZGER AND EWALD LÜTSCHEN, OF MUNICH, GERMANY.

HEAT-EXCHANGE DEVICE.

Original application filed May 11, 1921. Serial No. 468,722, and in Germany August 8, 1919. Divided and this application filed October 5, 1922. Serial No. 592,635.

This invention relates to a device for collecting the heat of compression from gases for the purpose of utilizing such collected heat and at the same time reducing the temperature of the gases.

The invention has for its primary object to provide a simple and compact device for the above purpose in which provision is made for the abstraction of the heat from the compressed gases at the time of compression and for collecting the relatively cool compressed gases in a chamber from which they may be withdrawn and utilized for various purposes. Further, we propose in one embodiment of the invention to advantageously utilize the abstracted heat, as for the purpose of supplying a suitable heating medium from an external source to the cylinder or cylinders of an engine.

It is also an object of our present improvements to provide such a device whereby the heat is abstracted as the gases are compressed.

With the above and other objects in view, the invention consists in the improved device as hereinafter more particularly described, illustrated in the accompanying drawing, and subsequently incorporated in the subjoined claims.

Fig. 1 is a central section partly in elevation of our improved device. Fig. 1^a is a diagrammatic view of the same showing parts of the structure of Fig. 1. Fig. 2 is a section taken on line 2—2 of Fig. 1 and Fig. 3 is a section taken on line 3—3 of Fig. 1.

In the drawing, wherein we have illustrated one simple embodiment of the invention, we have shown a vertical sectional view of the device with certain parts thereof in elevation.

In the example of our present improvements shown in Fig. 1, the compressor cylinder indicated at 1 may be of any suitable bore diameter within which the usual piston having the predetermined length of stroke operates. In the present instance, we have shown said cylinder as being vertically disposed, though of course this is not essential, and at one of its ends this cylinder is provided with a head 2 suitably secured thereon. In spaced relation to the cylinder head and supported therefrom by the pillars 3 we provide the wall 4. As will be herein-after explained, in certain instances it may

be desirable to substitute a continuous wall preferably of insulated material for the pillars 3 to thereby provide a closed chamber between the head 1 and wall 4.

In the form of invention shown in Fig. 1 the wall 4 forms the bottom of a chamber 5 having a valve 8 therein of general conical form guided at its apex by the guide means 10 on one wall of said chamber and provided at its other end with an annular inclined surface which is normally held in contact with a valve seat 11 in the wall 4 by means of the spring 9. The valve seat 11 is formed at one side of a chamber or cavity 7 in the wall 4 and a plurality of relatively small diameter tubes or pipes 6 communicate at one of their ends with the opposite side of this chamber, said tubes preferably converging to said chamber from their other ends which are fixed in the cylinder head 2 and open upon the inner face thereof.

From the above description, it will be apparent that the compressed gases in the cylinder 1 are forced under pressure by the piston through the small diameter tubes or pipes 6 and into the cavity 7. The spring 9 offers such resistance to the opening movement of the valve 8 that before the gases are admitted to the chamber 5, the heat of compression is abstracted therefrom by radiation through the walls of the tubes 6 and is either dissipated into the atmosphere or is collected in the chamber 2^a formed between the cylinder head 2 and the wall 4. If desired, in order to augment the abstraction of heat from the compressed gases in said tubes, water may be circulated through said chamber and the heated water withdrawn therefrom and conducted to a relatively remote point for utilization. Also, if desired, the cylinder head 2 as well as the wall 4 may consist of materials which are of high heat absorbing capacity but which will release or radiate the heat very slowly. It is preferable to make the cylinder head 2 or the wall 4, or both of copper.

When the compressed gases have accumulated in the cavity 7 to such extent that the pressure thereof exceeds the pressure of the spring 9, the valve 8 is lifted from its seat so that the relatively cool compressed gases will enter the chamber 5. From this chamber the compressed and cooled gases may be withdrawn and utilized for various purposes.

From the above, it will be seen that the

invention has a two-fold purpose, namely, first to abstract the heat from the compressed gases and thereby cool the same, and secondly, to collect such abstracted heat and apply the same to an advantageous use.

The number of pipes or tubes 6 to be employed and their individual cross sectional area, as well as their aggregate area is of course, determined in accordance with the capacity of the compression cylinder 1 and the volume of gas which can be compressed therein and whereby, after the gases have passed into these tubes or pipes beyond the cylinder head 2, the heat of compression will be abstracted therefrom before the valve 8 is lifted and the gases admitted to the chamber 5.

This application is a division of our pending application for patent, Serial No. 468,722, filed May 11, 1921. While we have herein disclosed one practical example of the device, it will nevertheless, be understood that substantially similar results might be obtained in various alternative forms thereof, and we therefore, reserve the privilege of resorting to all such legitimate changes as may be fairly embodied within the spirit and scope of the appended claims.

We claim:

- 30 1. A device for abstracting the heat of compression from gases comprising, a compressor cylinder, a chamber arranged in spaced relation to the cylinder head and having an ingress opening, a spring seated valve within said chamber normally closing said

opening, and a plurality of relatively small diameter tubes communicating at one of their ends with said ingress opening and at their other ends with the end of the compressor cylinder, said tubes adapted to receive the compressed gases from said cylinder and give up the heat of compression through the tube walls during the travel of the gases through said tubes and prior to the accumulation of sufficient pressure at the ingress opening to open said valve and admit the gases to said chamber.

2. A device for abstracting the heat of compression from gases comprising, a compressor cylinder, a wall supported by one of the cylinder heads and spaced therefrom and having a central cavity therein, a chamber at one side of said wall into which said cavity opens, a spring seated valve normally closing the open side of said cavity, and a plurality of spaced tubes of relatively small diameter connecting said cavity with the end of the compressor cylinder and adapted to receive the compressed gases from the latter and to give up the heat of compression therefrom through the tube walls into the space between said cavity and the cylinder head, the relatively cool gases collecting in said cavity and the accumulated pressure thereof opening said valve to admit the cool gases to said chamber.

In testimony whereof we herewith affix our signatures.

CARL METZGER.
EWALD LÜTSCHEN.
